Attnys.

a horizontal partition extending across the casing intermediately of the height of the same and dividing the casing into upper and lower hot air chambers, a vertical partition 5 situated between the horizontal partition and the bottom of the casing, and having vents therethrough in the vicinity of its upper end, said horizontal partition having vents therethrough communicating with the lower part of the casing inside the said vertical partition, dampers for closing such 10 vents, a cold air inlet at the bottom of the furnace, a cold air pipe leading from the bottom of the furnace to the upper hot air chamber through the lower hot air chamber and the bottom of said casing having vents 15 therein for admitting cold air to the lower hot air chamber.

3. In a furnace, the combination with the fire box, of a casing surrounding the fire box, a horizontal partition extending across the casing intermediately of the height of

the same and dividing the casing into upper and lower hot air chambers, a vertical partition situated between the horizontal partition and the bottom of the casing, and having vents therethrough in the vicinity of its upper end, said horizontal partition having vents therethrough communicating with the lower part of the casing inside the said vertical partition, dampers for closing such 25 vents, a cold air inlet at the bottom of the furnace, a cold air pipe leading from the bottom of the furnace to the upper hot air chamber through the lower hot air chamber, the bottom of said casing having vents 30 therein for admitting cold air to the lower hot air chamber, conduits communicating with the lower portion of the casing, registers at the ends of said conduits, dampers in 35 said conduits and hot air pipes leading from the upper part of the casing.
